[57] **CLAIM**

The ornamental design for a beverage can, as shown and described.

DESCRIPTION

FIG. 1 is an isometric view of a beverage can showing my new design;

FIG. 2 is a front elevational view thereof;

FIG. 3 is a rear elevational view thereof;

FIG. 4 is a left side elevational view thereof;
FIG. 5 is a right side elevational view thereof;
FIG. 6 is a top plan view thereof; and,
FIG. 7 is a bottom plan view thereof.

The broken lines showing the bottom and top of the beverage can are for illustrative purposes only and do not form part of the claimed design.
